UNITED STATES PATENT OFFICE.

JOHN W. HADDOX, OF PARKERSBURG, WEST VIRGINIA.

KNOCKDOWN MANTEL.

1,171,717.

Specification of Letters Patent. Patented Feb. 15, 1916.

Application filed June 23, 1915. Serial No. 35,840.

To all whom it may concern:

Be it known that I, JOHN W. HADDOX, a citizen of the United States, residing at Parkersburg, in the county of Wood and 5 State of West Virginia, have invented new and useful Improvements in Knockdown Mantels, of which the following is a specification.

This invention relates to a mantel of the 10 knock down type designed primarily for ornamental purposes, and which is commonly termed a cabinet mantel.

The primary object of the invention is to 15 provide a mantel of this character which is formed from a plurality of detachable sections, which may be detached or assembled as the occasion may require.

The improved mantel is so constructed 20 that it may be used as a base mantel, which is usually a mantel without a mirror but provided with ornamental cornices, or the detachable sections of the mantel may be adjusted to form a half cabinet mantel, which comprises a base and a mirror, or the 25 detachable sections may be connected in such a manner as to provide a full cabinet mantel, which includes a base, a mirror, and an ornamental cornice above the mirror.

A still further object of the invention is 30 to provide a knock down cabinet mantel comprising detachable sections which may be neatly compact for shipment or for storage if desired, and to provide a mantel which may be formed entirely of sheet metal.

With these and other objects in view, the 35 invention resides in the novel arrangement and combination of parts, which will be hereinafter fully described and particularly 40 pointed out in the claims.

The preferred embodiment of the invention 45 has been illustrated in the accompanying drawings, although no restriction is necessarily made to the precise details of construction therein shown, as changes, alterations, and modifications within the scope of the claims may be resorted to when desired.

In the drawings:—Figure 1 is a face view 50 of the improved knock down mantel constructed in accordance with the invention, the same being shown as a mantel of the type known as a full cabinet mantel. Fig. 2 is a front elevation of the mantel showing the same formed from the detachable sections to provide a half cabinet mantel. Fig.

3 is a section on the line 3—3 of Fig. 1. Fig. 4 is a section on the line 4—4 of Fig. 1. Fig. 5 is a transverse sectional view on the line 5—5 of Fig. 1. Fig. 6 is a transverse sectional view on the line 6—6 of Fig. 1. Fig. 7 is a detail perspective view of one of the sides of the mantel showing the shelf and mirror section detached therefrom. Fig. 8 is a detail perspective view of the reverse side of the mirror section from that shown in Fig. 1. Fig. 9 is a detail perspective view of the detachable cornice section showing the reverse side of the same from that shown in Fig. 1. Fig. 10 is a detail perspective view of the reverse side of the cross piece from that shown in Fig. 1 of the drawings.

Like characters of reference denote corresponding parts throughout the several views in the drawings.

The numeral 1 designates a full cabinet mantel constructed in accordance with the invention, which comprises the base 2, a mirror section 3 which may be detachably connected with the side members of the 50 base, a cornice 4 adapted to be supported upon the mirror section, and a shelf 5 detachably connected with the side members and supported upon the columns and cross piece of the base section.

The base section 2 includes a pair of vertical side members 6 which are identical in construction and which are formed of sheet metal. Coöperative with the side members 6 to form the base section is a cross piece 7 85 which is also stamped from sheet metal. The side members 6 and cross piece 7 may be suitably ornamented by stamping into the sheet metal some suitable design.

The side members 6 are formed from detachable sections 8 and 9, the section 8 being U-shaped in cross section and of greater length than the sections 9. The sections 9 are channeled to provide pilasters 10 which extend the full length of the sections 9 and 100 may be formed in the shape of a column if desired. The ends of the sections 9 are bent at right angles to the channeled portion of said sections to provide flanges 11 and 11', the flanges 11 of the sections being provided with a series of openings adapted to receive fastening elements 12 for securing the sections 9 to the sections 8, while the flanges 11' are provided with a series of apertures 105 to receive fastening elements 12', similar to 110

those designated by the numeral 12 and by means of which the cross piece 7 is secured to the sections 9.

The channeled portions 10 of the sections 5 9 are adapted to receive a casing 13 which is secured thereto in any suitable manner in order that the casings may provide a base for the pilasters, while the capitals of the pilasters are provided with an ornamented 10 annular ring member 14 which may be secured in any manner desirable to the upper portion of the pilasters to form the capital therefor.

Under each of the side members 6 and extending within the pilasters 10 is a base 15 which prevents the side members and pilasters thereon from becoming distorted while the mantel is in a knock down condition. Each side member 6 is further provided 20 with an aperture 16 adapted to receive a screw or similar fastening element which may be inserted within the wall to which it is desired to attach the mantel.

The cross piece 7 is U-shaped in cross 25 section and is adapted to be interposed between the side members 6 and detachably connected therewith to assist in supporting the shelf 5 and also to prevent the spreading of the side members when the mantel is assembled.

The shelf 5 like the cross piece 7 is U-shaped in cross section and has one of the side walls thereof provided with an upstruck portion terminating in a flange 17 spaced 35 from the end of the shelf, as indicated at 17. The flange 17 of the upstruck portion is adapted to rest upon the upper wall of the cross piece 7, and is secured to said cross piece by fastening elements such as screws, 40 or the like, as indicated at 18.

The mirror section 3 is of a width corresponding to the outermost side walls of the sections 9, and of a height corresponding to the height of the section 8 extending above 45 the shelf 5, and has the side and top edge thereof formed with a flange 19 which maintains the mirror section spaced from the sections 8 and forms an attaching portion for the cornice of the mantel. The mirror section 50 is recessed, as at 20, and the edges of the sections surrounding the recess are bent to provide a flange for receiving the edges of the mirror 21 which is secured within the said flange in any suitable manner. The 55 mirror section 3 is detachably connected with the sections 8 by means of brackets 22 each of which has one end thereof adapted for insertion in a slot 22' in the sections 8 and the remaining end slotted and adjustably connected with the mirror section in order that the sections 8 and mirror section 3 may be maintained in an assembled condition when the mantel is set up.

The flange upon the upper side wall of the 65 section 3 is provided with a series of longi-

tudinally extending apertures 23 to receive fastening elements such as screws having eyes or the like for securing the cornice section 4 to the mirror section.

The cornice section 4 may be of any suitable configuration which would serve to ornament the top of the mirror section when the cornice section is attached thereto, but in this instance the cornice section has been shown as comprising a longitudinally extending channeled member superimposed upon the mirror section by means of slots 24 in the flanged side wall 25 of the cornice section, said slots being adapted to receive the fastening elements extending through the 80 series of apertures in the flange of the mirror section.

In practice when it is desired to assemble the mantel the sections 9 are secured to the sections 8 of the cross piece 7 secured to the 85 sections 9. The shelf 5 may then be secured to the cross piece and positioned upon the sections 9 in the manner above described if it is desired to have the above-mentioned sections form the cabinet mantel when assembled.

Should it be desired to provide a half cabinet mantel the mirror section may be connected with the shelf and the sections 9 of the side members 6 in the manner above 95 described, and in this way a half cabinet mantel is provided. If a full cabinet mantel is desired the cornice section may be secured to the flange on the top of the mirror section, thus providing a full cabinet mantel.

It will of course be understood that the mantel may be disassembled in a manner opposite to that described for assembling the same to form a cabinet, half cabinet, or a full cabinet mantel, and attached to a wall 105 or support by means of fastening elements and the openings 16 in the sections 8.

From the foregoing statement it is readily apparent that a mantel construction has been provided which may be formed from 110 sections stamped from sheet metal, and which may be easily assembled or disassembled as the occasion may require, furthermore a mantel construction is provided which may be ornamented as desired and covered with veneer to simulate a wood mantel now in use. It will also be noted that the sections form a mantel which is inexpensive of manufacture, durable in construction, and highly efficient in use, and also that a mantel constructed from the sections would be comparatively light in weight in comparison with the mantels now in use.

Having thus described the invention, what is claimed as new is:

1. A mantel having channeled side members extending vertically in spaced relation and each provided with a slot in one side wall, a shelf, means for supporting said shelf, a mirror section, a bracket adjustably 130

connected with the rear face of the mirror section at opposite sides thereof, said brackets each having an end lying in a plane parallel with the rear face of the mirror section and in spaced relation therewith for insertion in a slot in the side wall of one side member, a flange on the mirror section provided with spaced and headed studs, and a cornice section provided with a flange having spaced slots therein adapted to receive said studs beneath the heads thereon.

2. A mantel having channelled side members extending vertically in spaced relation, said side members each having a vertical row of openings in the front face thereof, pilasters each having a flange upon opposite sides, one of said flanges upon each pilaster lying in a plane parallel with the front face of one of said side members and provided with openings registering with openings in the side members, means for connecting the pilaster with the side members passing

through said openings, a mirror section, means adjustably mounted on the mirror section for connecting the mirror section with the side members a channeled cross piece connected with the remaining flanges on the side members and provided with a side wall having spaced openings, a shelf U-shaped in cross section disposed upon said pilaster and provided with a side wall having an up-struck portion terminating in a flange, for contact with the side wall of the cross piece, said flange having openings therein registering with the openings in the side wall of the cross piece, and means for fastening the shelf to the cross piece passing through said openings.

In testimony whereof I affix my signature in presence of two witnesses.

JOHN W. HADDOX.
